UNITED STATES PATENT OFFICE

168,932

FLASK

Sophie Frydlender, Paris, France, assignor to Lancome, S. A., Paris, France, a corporation of France

Application April 28, 1951, Serial No. 15,005

In France July 12, 1950

Term of patent 14 years

(Cl. D58—6)

To all whom it may concern:

Be it known that I, Sophie Frydlender, a citizen of the Republic of France, residing at Paris, France, 14 rue Lamblardie, have invented a new, original, and ornamental Design for a Flask, of which the following is a specification, reference being had to the accompanying drawing, forming a part hereof.

I claim:

The ornamental design for a flask, as shown.
SOPHIE FRYDLENDER.
